R. L. Harrington

UNITED STATES PATENT OFFICE.

WILLIAM J. NEWMAN, OF CHICAGO, ILLINOIS.

END GATE FOR DUMP TRUCKS.

Application filed April 8, 1920. Serial No. 372,480.

To all whom it may concern:

Be it known that I, WILLIAM J. NEWMAN, a citizen of the United States, residing at Chicago, in the county of Cook and State 5 of Illinois, have invented certain new and useful Improvements in End Gates for Dump Trucks, of which the following is a specification.

This invention relates to an end gate or door, which is especially adapted to be used for the bodies of automobile trucks having means for tipping or tilting the body for dumping the same. These trucks are frequently used for hauling various kinds of 10 material, including earth or excavated material, and are frequently filled by means of steam shovels. When these trucks are dumped, it is sometimes desirable to have the load discharged at some distance from 15 the rear end of the truck body, while at other times it is desirable to have the load discharged close to the body.

The objects of the present invention are to provide a simple form of end gate or 20 closure for truck bodies which may enable the load to be discharged close to the end, or at some distance therefrom; to provide an end gate having combined pivots and catches at the top and bottom thereof, where- 25 by the gate may be swung upwardly or downwardly to discharge the load; to provide an arrangement whereby the gate may be swung up above the top of the body, to insure a full discharge space; to provide a 30 combined catch and hinge member for an end gate; and in general, to provide such an improved construction as will be described hereinafter.

In the accompanying drawings showing 35 one form of my device:

Figure 1 is a side view of the rear end of a truck body shown in discharging position;

Figure 2 is a detail plan view of the hinge 40 arrangement.

As shown in these drawings, 3 represents a truck body which may be of any ordinary or preferred form of construction, and which is provided with an end gate 4, which is 45 connected at its lower edge, to the body by combined hinge and catch devices, whereby the door may swing or be freed at its lower edge. In the present instance, these combined hinges and catches comprise U-shaped bearings 5, which are se-

cured to the body 3, and are adapted to receive the pintles 6 which project from the lower edge of the door 4. The bearings 5 are provided with holes 7 for receiving locking pins 8, for holding the pintles in 60 position.

The upper edge of the door is provided with hinge arms 9, which project forwardly and have pintles 10, which rest on the top of the box or body 3 which is formed so that it furnishes a suitable bearing therefor. As shown in the drawings such bearing is provided by having plates or flanges arranged at the top of the sides of the body 70 3, this being a more or less common form of construction in bodies for trucks intended for heavy loads. Hooks 11 are hinged at 12 to the upper portions of the sides of the body, and engage with the pintles 10 to hold them in proper position. These hooks preferably extend through holes 75 13 in the upper part of the sides, and are also preferably provided with handles 14 for swinging the same. It will be seen from the drawings that when these hooks are moved downwardly to engage with the pintles or hinge member 10, they draw in on these members to draw the end gate tight and then hold it in this position. These hooks with their hinge straps being positioned on the top of the box, also serve to 80 protect the same, as they are preferably made quite strong and heavy.

When the door or gate 4 is to be used as a chute for discharging material some 90 distance from the end of the body, the hooks 11 are raised, and the gate swings outwardly from the top to the lowered position shown in dotted lines in Figure 1.

When the gate is to be swung upwardly, 95 the pins 8 are removed and the gate may then swing on the upper hinges to the raised position shown in dotted lines in Figure 1. It will be seen that when the gate is in this position, it is lifted bodily above the box, 100 a distance depending upon the length of the arms 9. This is for the purpose of making a free passageway for dirt or lumpy material which might project above the body and would strike the door if it were swung from its upper edge. It will be particularly noted that this provides means for elevating the gate without having any parts projecting for any considerable distance above the body. This is an important feature, as 110

any projecting parts are apt to interfere when the trucks are being loaded by steam shovels.

It will be noted that changes may be made in the details of construction to adapt this invention to different forms of bodies, and means (not shown) may be provided for manipulating the catch members from the driver's seat, and therefore I do not wish 10 to be limited to the exact arrangement herein shown and described, except as specified in the following claims:

1. The combination with a truck body having outwardly projecting flanges at the 15 top thereof with holes therethrough, of hinge members secured to the flanges, hooks pivoted to said hinge members and adapted to project down through said holes in the flanges, said hooks having handles for 20 swinging the same, an end gate pivoted at the bottom of the body and having pins

adapted to rest on the flanges in advance of the hooks and to be engaged by the hooks for holding the door in closed position and also to provide a hinge whereby the bottom 25 of the door may be swung outwardly, substantially as described.

2. The combination with a truck body having flanges at the top thereof, of an end gate, combined hinge and catch fastenings 30 at the bottom of the gate, pins at the top of the gate adapted to rest on the flange, hooks pivotally secured to the flange and projecting downwardly through holes behind the pins and adapted to engage with 35 the pins for holding the gate in closed position and also for providing a hinge for the gate, said hooks being arranged so that they project a minimum distance above the top of the body, substantially as described.

WILLIAM J. NEWMAN.
